A. F. HECHT

WASHING MACHINE

Filed Sept. 16, 1922

INVENTOR
A. F. Hecht
BY *Maurice Leo*
ATTORNEYS

UNITED STATES PATENT OFFICE.

ALBERT F. HECHT, OF WORTH, ILLINOIS.

WASHING MACHINE.

Application filed September 16, 1922. Serial No. 588,698.

To all whom it may concern:

Be it known that I, ALBERT F. HECHT, a citizen of the United States, and a resident of Worth, in the county of Cook and State of Illinois, have invented a new and useful Improvement in Washing Machines, of which the following is a full, clear, and exact description.

My invention relates to improvements in washing machines and it consists in the combinations, constructions, and arrangements herein described and claimed.

An object of my invention is to provide a washing machine which is constructed in a novel manner so that in operation the water in the machine is moved so as to always keep the clothes agitated and to prevent the rolling up of the clothes into small wads.

A further object of my invention is to provide a device of the type described in which the clothes are moved to the sides of the machine, and are then carried upwardly and back to the center of the machine, whereby the clothes are effectually agitated.

A further object of my invention is to provide a device of the type described which also has means for causing the water to rotate within the container in either direction.

A further object of my invention is to provide a device of the type described which is substantially balanced, whereby the operating of the device is easily done.

A further object of my invention is to provide a device of the type described which is simple in construction, durable and efficient for the purpose intended, and which is not likely to easily get out of order.

Other objects and advantages will appear in the following specification, and the novel features of the invention will be particularly pointed out in the appended claims.

My invention is illustrated in the accompanying drawings forming part of this application, in which

Figure 1 is a side elevation of the device, Figure 2 is a plan view of the device, and Figure 3 is a front elevation of the device.

In carrying out my invention I provide a supporting frame 1 which is triangular in shape. The side 2 of the frame is in the shape of a rocker and is adapted to swing the tub 3 out of horizontal position when the device is actuated. A crank pin 4 is disposed at the junction of the sides 5 and keeps the sides from engagement with the

supporting surface. It will therefore appear from this construction that the device is only supported by the rocker 2 and the pin 4. When the device is set in operation, the rocker will oscillate the tub, and the pin 4 will cause the tub to swing through an arc. These two movements give a peculiar movement to the water within the tub which will be hereinafter more fully described. Moreover, by swinging the crank pin into various positions, the movement of the water can be changed at will. A tub supporting frame 6 is secured to the frame 1, and effectually supports the tub 3. It should be noted that I have described one specific form of the device, altho many modifications may be made without departing from the spirit and scope of my invention. The principal object of the invention is to rock a circular tub through a portion of a circle, the center of the circle being varied at will, whereby the water within the tub is given a certain definite motion which is not obtainable with devices constructed along a different design.

From the foregoing description of the various parts of the device, the operation thereof may be readily understood. A handle 7 is provided for the tub by means of which the device is operated. It is obvious that a mechanical means could be readily attached to the device to take the place of the manual operation if desired.

The peculiar movement of the water within the tub is as follows. Assume that the device is actuated so as to rock the tub in the direction of the arrows shown in Figures 2 and 3. The water within the tub would move in the direction of the dotted arrows shown in Figure 2. It will be noted that two currents of water are flowing and that they cross each other at the center of the tub. These currents carry the clothes to one side of the tub. If the tub did not describe an arc in its movement, there would be only one current which would be parallel with the direction of travel. By swinging the tub through an arc, two cross currents are started which effectually separate the clothes at the center of the tub and carry them to the side of the tub.

When the device swings in the opposite direction, the momentum of the water causes it to pile up against the side of the tub and to splash back over the body of the water within the tub, to the center of the tub, (see Figure 3). Two waves of water

are started by the two currents, these two waves falling back into the center of the tub and meeting each other at this point. The clothes are therefore carried by the waves back to the center of the tub. In this manner the clothes are first carried from the center of the tub to one side of the tub, and then back over the body of water to the center of the tub. This same movement of water takes place in the opposite direction when the tub is swung into its farthest position in the opposite direction of the arrow. The cross currents break up the clothes at the center of the tub and thus prevent the clothes from bunching.

If desired, the water in the tub can be given a circular motion in either direction. This is accomplished by swinging the pin 4 to either side of the frame 1. When the pin is on one side of the frame, the water will rotate a little distance in the circular tub during each swing of the device. The rotating movement of the water carries the clothes from the side of the tub around to where the cross currents are taking place. It will further be noted that the water from the cross currents when striking the wall will move laterally to a slight degree. These various movements of water thoroughly agitates the clothes and thus effectually washes them.

I claim:

1. A washing machine comprising a

clothes containing receptacle, and a frame for supporting said receptacle, said frame being supported by a curved member and a pin, whereby said receptacle is oscillated through an arcuate shaped path, said pin being adjustable with respect to said frame, whereby the path of said receptacle is altered at will.

2. A washing machine comprising a frame supported by an arcuate-shaped runner and an adjustable pin, and a cylindrical tub carried by said frame.

3. A washing machine comprising a frame having an arcuate-shaped runner and a pin spaced from said runner at a point equidistant from the ends of the runner, and a cylindrical tub carried by said frame.

4. A washing machine comprising a frame having an arcuate-shaped runner and a crank pin spaced from said runner at a point equidistant from the ends of the runner, said crank pin being adjustable, and a cylindrical tub carried by said frame.

5. A washing machine comprising a frame having an arcuate-shaped runner on which the frame is adapted to rock, a crank pin carried by said frame and being spaced equi-distant from the ends of said runner, said pin being adapted to be turned with respect to said frame, and a cylindrical tub carried by said frame and being disposed above the runner.

ALBERT F. HECHT.
